DANIEL R. FRANCIS, OF WATERBURY, CONNECTICUT, ASSIGNOR TO THE WATERBURY TOOL COMPANY, OF WATERBURY, CONNECTICUT, A CORPORATION OF CONNECTICUT

WINDER DRIVE FOR PAPER MACHINES

Application filed January 9, 1929. Serial No. 331,370.

The invention relates to paper machines and more particularly to the winder drives of that class of such machines in which webs of paper are wound in the form of rolls. In 5 machines of the indicated type the efficiency of the winding means varies at times with the product which is being handled, and difficulty has been experienced in producing rolls of uniform density and with the desired hard 10 centers, when such variations develop. Furthermore, with many existing types of winder drives it is necessary, when threading-in, to turn the mechanism over by hand in order to 15 avoid a jerking motion which results from the use of a slip belt or from slipping the clutch which causes a jerking motion liable to break the sheet, and dangerous to the operators. To turn the winder by hand is objectionable, as the motion is then produced 20 in a series of steps, while practice has shown that only a slow uniform motion will produce the start of a high grade roll. Furthermore, after the roll has been started, it is necessary to quickly bring the winder to full 25 speed in order to obtain the maximum production. On a given machine, it is desirable to be able to operate the winder at a number of different speeds so that the speed at which one sheet may be efficiently handled shall 30 not be limited by a very much weaker sheet made, for instance, on the same paper machine.

The object of the present invention is to 35 provide a driving means whereby the above objections will be automatically overcome and the desired advantages automatically obtained, and whereby the operator will be given full control over his machine, both in speeding up and slowing down to a full stop 40 without the use of a brake and without any jerks or sudden variations in the speed.

The invention contemplates further the 45 provision of a driving means which will facilitate the threading-in process and provide a smooth and uniform acceleration from the threading-in speed to the running speed with a constant, even tension on the sheet to thereby avoid breakage of the latter and the delay and waste resulting therefrom. Other more 50 specific objects will appear from the descrip-

tion hereinafter and the features of novelty will be pointed out in the claims.

In the accompanying drawings, which illustrate examples of the invention without defining its limits, Fig. 1 is a front elevation 55 of a winding machine embodying the novel driving means; Fig. 2 is a diagrammatic sectional elevation; Fig. 3 is a fragmentary view showing another driving arrangement; Fig. 4 is a view similar to Fig. 1 illustrating 60 still another form of drive, and Fig. 5 is a detail view, partly in section, of the driving means.

The winding machine itself may be of any conventional construction and include any of 65 the features generally found in such machines, or provided in special forms thereof; the novel driving means is particularly adapted to that type of winding machines which include two drums 10 and 11, suitably 70 journaled in a conventional frame 12 in proximity to each other as shown in Fig. 2 to provide a rotating support on which the roll of paper 13 is adapted to rest. The web of paper 14 may reach the winding machine 75 from any suitable source, as, for instance, a supply roll 15 suitably supported on the frame 12 and passes over a plurality of tension rolls 16 located in the machine in the usual manner. The required tension on the sheet 80 or web being wound is obtained in any suitable manner as for instance by means of an overhead idler or pressure roll 17, sometimes called the rider roll and resting upon the surface of the roll 13 being wound, as shown 85 in Fig. 3.

The improved driving means comprises a fluid pressure motor 18, to which fluid under pressure is circulated by means of a variable delivery pump 19. The fluid pressure motor 90 18 and the delivery pump 19 may be constructed as a unit, as shown in Fig. 4, and communicate with each other through a suitable valve plate 20, or the delivery pump may be constructed as a separate independent unit 95 and located at a distance from the motor 18, in which case the pump is connected with the motor 18 by means of suitable pipes. The variable delivery pump 19 is of the well known type of pumps employed for variable speed 100

gears, and consists of a driving shaft 21 on which is mounted a rotatable barrel 22, provided with a plurality of cylinders 23 extending in parallel relation to the shaft 21. 5 Each cylinder 23 slidably accommodates a piston 24, which is connected by means of a piston rod 25 with a swash plate 26, rotatably mounted in an adjustable tilting box or race 27. The latter and with it the swash plate 10 26 may be adjusted to different angles of inclination relatively to the driving shaft to vary the strokes of the pistons 24 and therefore the output or the amount of fluid delivered by the pump for each revolution of the 15 cylinder barrel 22. The means for adjusting the inclination of the swash plate will be more fully described hereinafter.

In the examples of the invention illustrated in the drawings, the motor 18 is similar in construction to the pump 19, excepting that the swash plate 26 and tilting box 27^a of said motor are located at a fixed angle of inclination with respect to the driving shaft 21^a of said pump 19. The pump 19 may be 25 driven in any convenient manner and by any suitable means, and in the illustrated example has its shaft 21 directly coupled, for instance, by means of a flexible coupling 29 with the armature shaft of an electric motor 30. Similarly, the driving shaft 21^a of the motor 18 may be connected with the drum 10 and 11 in any conventional way, as by extending the shaft 31 of the roller 10 and supporting said extension in an outboard bearing 32. On the end of the shaft 31 a gear 33 is mounted in mesh with a gear 34 fixed upon the shaft 21^a of the motor 18. In some cases as shown in Fig. 3, the shaft 21^a of the motor 18 may be directly connected with the 40 shaft 31 of the drum 10 and provided with a gear 35 meshing with an idler gear 36 which in turn engages a gear 37 on the shaft of the second winder drum 11 so that both drums are driven at the same speed and in the same 45 direction. If it is desired to provide a means for driving the drum 11 either at the same or at a different speed from that of the drum 10 to produce a tension on the sheet being wound, the shaft 21^a, as shown in Fig. 4, may be coupled to the end of a short counter-shaft 38 on which are mounted a straight pulley 39 and a tapered pulley 40. The straight pulley 39 is connected by means of a belt 41 with a similar pulley 42 mounted 50 on the shaft 31 of the drum 10, while the tapered pulley 40 is similarly connected by means of a belt 43 with a correspondingly tapered, but oppositely arranged pulley 44 located upon the shaft of the drum 11. By 55 shifting the belt 43 on the cone or tapered pulleys 40 and 44, the speed of the drum 11 may be slightly varied with respect to the speed of the drum 10 to produce a tension on the sheet or web 14 as it is being wound on the roll 13.

The means for adjusting the swash plate 26 of the delivery pump 19 may be of any suitable type and as shown consists of a control shaft 45 extending transversely to the shaft 21 and journaled in a suitable bearing 45^a, as 70 shown in Figs. 1, 4 and 5. The control shaft 45 is connected with the swash plate 26 by means of a bearing block 46, slideable in a forked arm comprising an integral part of the tilting box 27 and connected with a stub shaft 47, which in turn is connected with the control shaft 45. In the preferred arrangement, the control shaft 45 extends in opposite directions beyond the bearing block 46 and is provided at its opposite ends with threaded portions adapted for screwthreaded engagement with internally threaded nuts 48 or 49 as the case may be, said nuts being suitably held against movement in axial directions but free to rotate relatively to said control shaft 45. Manually operated means are provided for selectively adjusting the control shaft 45 of the pump, said means co-operating with either one or the other of the threaded ends of the control shaft 45, dependent upon local conditions existent in any given installation. In the form shown in Fig. 1 the upper end of the shaft 45 is in screwthreaded connection with the manually operated means, which as shown consists of a bevel gear 50 connected with or forming an integral part of the aforesaid nut 48 and meshing with a bevel gear 51 carried by a shaft 52, journaled in bracket bearings 53 and extending transversely across the machine, as shown in Fig. 1. To facilitate the operation of the shaft 52, it may be provided with a hand-wheel 54 as shown in Fig. 1.

If for any reason it is more desirable the arrangement shown in Fig. 4 may be used in which a bevel gear 50^a, corresponding to the bevel gear 50, is connected with or forms part of the nut 49. This bevel gear 50^a meshes with a bevel gear 51^a fixed upon a shaft 52^a journaled in suitable bearings 53^a 100 and extending transversely across the machine at the bottom thereof as shown in Fig. 4. To facilitate the operation of this arrangement of the manually operated means, the shaft 52^a may be provided with a sprocket wheel 55 connected by means of a sprocket chain 56 with a corresponding sprocket wheel 57 secured upon a stub shaft 58 which in such case carries a hand wheel 54^a corresponding to the hand wheel 54 and likewise located 110 within easy reach of the operator. It will be understood that either of the control shafts 52 or 52^a may be used in a machine dependent upon existing local conditions, and further, that generally speaking, only one of said 120 shafts with its co-operating parts is necessary.

When the tilting box 27 and the swash plate 26 are perpendicular to the shaft 21, or, in other words, in the "neutral position", 130

the pistons 24 have no stroke and consequently no fluid is pumped. Adjustment of the control shaft 45 by means of either of the aforesaid control shafts 52 or 52^a to tilt the tilting box 27 and with it the swash plate 26 regulates the strokes of the pistons 24 and causes the output of the pump to be increased or diminished as the angle of inclination of the swash plate 26 increases or decreases with respect to the shaft 21. When the swash plate 26 is inclined in one direction, one of the ports of the valve plate becomes the pressure port, while the other port thereof becomes the suction port, while in the oppositely inclined positions of the swash plate, the pressure and suction ports are reversed, that is to say, the port which previously was the pressure port becomes the suction port, and the previous suction port becomes the pressure port. In operation and assuming that the control shaft 45 of the pump 19 is in its neutral position and that the electric motor 30 is started, the operation of said motor will cause the pump barrel 22 to be rotated, which rotation, however, will operate the pump without causing it to pump any fluid to the fluid motor 18, because of the setting of the control shaft 45 in its neutral position; as a result of this, there will be no rotation of the fluid motor 18. If it be desired to operate the drums 10 and 11 at a very slow speed, in order to permit the web 14 to be threaded-in, the hand-wheel 54 or 54^a is operated to adjust the swash plate 26 to a position in which a small quantity of fluid will be pumped to the fluid motor 18 to thereby cause the latter to rotate slowly, this slow motion being transmitted through the existing connections to the drums 10 and 11. In order to operate the winding machine at the desired running speed, the hand-wheel 54 or 54^a is further operated to adjust the swash plate 26 to a greater angle to thereby cause the strokes of the pistons 24 to be increased and the output of said pump 19 to be correspondingly increased, whereby the fluid motor 18 is driven at a correspondingly greater speed, which is transmitted by the aforesaid connections to the drums 10 and 11. To slow down the speed of operation or to completely stop the operation, the parts are actuated in a reverse direction, as will be readily understood.

With the arrangement set forth, the winder 55 drive provides a threading-in speed which may, if desired, be so slow that movement can scarcely be detected and permits adjustment from this latter speed to the maximum or any intermediate speed as slowly or as rapidly as the operator desires and in instant and exact response to any movement of the controlling means. The arrangement avoids the development of any working or jerking motion liable to break the sheet and permits the drive 60 to be adjusted in a manner to handle the web

of paper efficiently, regardless of its tensile strength, whether the same is constant or varies throughout the length of the web. Furthermore, the acceleration from the threading-in speed or from the position of rest to the running speed, or to any intermediate speed is smooth and uniform, so that the tension on the web is without variation and the danger of breakage of said web is positively avoided.

In addition to the above, the novel drive for the winding means makes it possible to tightly wind the web, commencing with the first wrap of the paper around the winding shaft, which tightness can be definitely and efficiently maintained up to the maximum diameter of the roll. The resulting rolls are consequently hard centered and of uniform density, which conditions can be varied to suit the different varieties of paper being 75 handled.

It has long been recognized that the problem of winding paper is one of tension. With the arrangement set forth herein, the tension may be applied to the web gradually, with the result that the strain on the web is lessened and injury to said web is reduced to a minimum. Furthermore, the driving means set forth herein permit the two drum principle of winding paper to be used efficiently and the utmost advantages thereof to be enjoyed. It is possible to operate the rear winding drum 11 at the same speed or at a slightly higher speed than the front drum 10, which travels at the same speed as the web, so that said web is automatically placed under a tension which materially improves the rolling thereof. The winding means is adapted for efficient use with all types of winding machines and may be adequately used in machines which include cutting devices for splitting the webs into individual strips.

Various changes in the specific forms shown and described may be made within the scope of the claims without departing from the spirit of the invention.

I claim:

1. The combination with a winder of a paper machine of the type wherein the roll of paper being wound is supported upon the periphery of a pair of winder rolls, of means for driving said winding rolls, for varying the speed thereof without interrupting breaks from zero to a predetermined maximum speed and for varying the speed of one of said winding rolls relatively to the other to cause a tension to be exerted for winding the paper roll into a hard center roll, said means comprising a fluid pressure actuated motor, a fluid pressure actuated pump for circulating fluid under pressure to said motor and power means for driving said pump, a driving connection of invariable effect between said motor and one of said winder rolls, and a 115

driving connection of variable effect between said motor and the other of said winder rolls.

2. The combination with a winder of a paper machine of the type wherein the roll of paper being wound is supported upon the periphery of a pair of winder rolls, of means for driving said winding rolls, for varying the speed thereof without interrupting breaks from zero to a predetermined maximum speed and for varying the speed of one of said winder rolls relatively to the other to cause a tension to be exerted for winding the paper roll into a hard center roll, said means comprising a fluid pressure actuated motor, a fluid pressure actuated pump for circulating fluid under pressure to said motor and power means for driving said pump, a driving connection of invariable effect between said motor and one of said winder rolls, a driving connection of variable effect between said motor and the other of said winder rolls, said pump being provided with a control shaft for infinitely varying the amount of fluid circulated by said pump from zero to a predetermined maximum and thereby producing a corresponding variation in the speed of said motor, a manually operable control handle located adjacent to said winding rolls and connections from said control handle to said control shaft of said pump.
